UNITED STATES PATENT OFFICE.

FRANZ AUSPITZ, OF VIENNA, AUSTRIA-HUNGARY.

COIN-CONTROLLED LOCKING DEVICE FOR SECURING ARTICLES.

SPECIFICATION forming part of Letters Patent No. 625,488, dated May 28, 1899.

Application filed June 23, 1898. Serial No. 684,203. (No model.)

To all whom it may concern:

Be it known that I, FRANZ AUSPITZ, constructor, a citizen of Austria, residing at Vienna, in the Empire of Austria-Hungary, have 5 invented certain new and useful Improvements in Coin-Controlled Locking Devices for Securing Articles, of which the following is a specification.

This invention relates to wall hooks or pegs 10 for securing articles of dress, sticks, umbrellas, and the like, more particularly in public places, which wall-hooks can either be used in the ordinary manner or they can be locked by the insertion of a coin, so as to securely 15 retain the objects suspended therefrom, and thus prevent their unauthorized removal. The opening of the locked hooks or pegs so as to liberate the articles can then only be effected by means of a special key, which is 20 retained by the person using the peg when this is locked, but which when the peg has been unlocked is retained in the keyhole of the mechanism. The key and the hook are marked with the same number, so as to prevent 25 confusion. Furthermore, a counter device can be applied indicating the number of coins that have been introduced and also an indicator for showing the number of articles that have been suspended upon the peg.

30 The improved peg device is shown on the accompanying drawings, in which—

Figure 1 shows a front view of the device in the locked position; Fig. 2, a side view, partly in section. Fig. 3 is a back view with 35 the peg in the locked position, some portions of the device being removed. Fig. 4 shows a back view of the hook in the open position with the cover-plate removed. Fig. 5 is a horizontal section of the device, taken just 40 above hook G. Fig. 6 is an edge view of the pivoted coin-tube, its support being in section.

The peg device consists of the hook, peg, or support B, fixed to the casing A, which is 45 suitably attached to the wall, and of the looped holder B', pivotally connected to the bracket a of the casing, which holder when in the closed and locked position fits with its front end close against the free end of the hook or 50 peg B and also fits with a forked arm B² partly around the peg, so that when clothes, &c., are hung upon the peg while B' is locked in this

position they cannot be removed. The inner end of the holder B' passes through a slot in the casing A and enters an opening in a slide 55 C, working vertically in guides in the casing and acted upon by a spring b, which tends to move it downward. The spring b bears with its one end against the casing and with its other end against a stud c on the slide C. 60 When thus moved downward, the slide consequently raises the outer end of the holder B' into position shown in dotted lines at Fig. 1, leaving the articles on B free to be removed. 65

When the holder B' is moved downward by hand into the closed position, it raises the slide C, whereupon a lever e, pivoted at its lower end to the slide and pressed forward by a spring d, is caused to project with a beak e' on its upper end over the upper end of a stop f on the casing, and thus to hold the slide in the raised position. If now it be desired to open the hook or peg by raising the holder B', the lever e must first be pressed backward, 70 which is done by means of a key D, which is passed through a keyhole in the casing. The beak e' being thereby removed from stop f, the spring b will now move the slide C down and raise the holder, as described. The key 75 is held in the keyhole when the slide is in the lowered position by a pin g, fixed to the latter, projecting through a hole or notch d' in the key, as shown at Fig. 4, and consequently the key can only be removed when the holder 80 B' is in the lowered locked position and slide C is raised, as at Figs. 1 and 3. The lowering and locking of the holder B' can, however, only be effected on the insertion of a coin into 85 the casing by the following arrangement: 90

To a partition h in the casing A is pivotally suspended a chute E, having a projecting stud i, which in the normal position of the chute E and open position of B' engages with a notch k in the slide C when this is in its lowest position, and thus prevents the upward motion of the slide and closing of the holder B'. For liberating the slide the chute E must therefore be swung backward on its pivot, so as to withdraw pin i from notch k. Such backward 95 motion of the chute is effected by the action of a coin M, inserted through the coin-slot l in the casing A. The coin slides down the chute E and bears at the bottom on the one 100

hand against a lateral projection m on the slide and also against the inclined back wall of the chute E . By the pressure thus exercised by the weight of the coin the chute is 5 pushed backward into the position shown in dotted lines in Fig. 4, whereby the pin i is withdrawn from notch k of the slide, which is consequently free to be moved upward by depressing holder B' . The chute E remains 10 in this position, still holding the coin until the holder B' has been pressed down and locked, as above described, whereupon the coin M , having been liberated by the projection m of the slide c in rising, can fall out of 15 the chute, and this will then swing forward into the normal position. The coin falls onto the bottom a' of the casing, which can be opened on a hinge for its removal and be then closed and locked. The holder B' having 20 been closed and locked, the key D is liberated, as before described, and can be removed and retained by the owner of the articles hung on the peg B .

The key is prevented from being thrown 25 out of the keyhole by spring of lever e when it is released by finger g by means of a lateral slot 3 on the key engaging with a pin 1 on the guide 2 of the keyhole. The key, however, is loose enough in the keyhole, and 30 pin 1 is short enough to allow the key to be readily removed when desired.

Each peg device and its key bear a corresponding number, so that no confusion can occur where a number of these pegs are employed, and it also facilitates the finding out 35 the particular peg required.

For hanging up a stick or umbrella a clamp G with spring-blade G' is pivoted to a projection a^2 of the casing A , the projection being 40 provided with a caoutchouc facing y . The tail of the clamp extends through a slot in the casing and bears with its angular end against a spring G^2 , that tends to hold it in either the open or the closed position. The 45 tail bears laterally against the slide C , which is formed with a wedge-shaped lower end C' , so that as the slide is raised into the locked position it pushes the tail of G outward, as at Fig. 3, and thus closes G and secures it in 50 the closed position, thus holding the stick or umbrella contained therein between the spring G and cushion y . When the holder B' is in the open position, the narrowed part C^2 of slide C is opposite the tail of G , as at 55 Fig. 4, so that this can be opened for removing the stick.

For indicating the number of times the locking device has been used, and consequently also the number of coins in the casing, a suitable counter device can be provided in the lower part of the casing, of which the principal actuating-disk H is shown at Figs. 2 and 3. This has divisions, (marked "1" to "10,") each of which has a projecting pin n , 60 on which acts an inclined projection o on the notched lower end of the slide C when this is moved downward. It will be understood that

the inclined side of part o strikes one of the pins when slide C is moved downward, and the length and inclination of part o are such as to move disk H forward one space for each downward movement of the slide. At the same time a projection p on C presses the spring q out of engagement with the notches on the periphery of H , so as to allow the incline o to readily turn the disk one division by the pin n , as described. The transmission 70 of the motion of disk H to a counter mechanism can be effected in any known manner. 75

For enabling the device to indicate the number of articles that are hung upon the peg there is provided in the upper part of the casing A a sliding bar r , provided with numbered disks, as at Figs. 1 and 3, which bar has a button I projecting through a slot in 80 the casing, by which it can be slid up and down. The bar has lateral notches, with which 85 engages a spring-catch v , which when the slide C is raised into the locked position is secured by an incline t on the slide, so that the bar r 90 is also locked in the position into which it has been slid by hand.

The above-described locking-peg is operated as follows: The holder of the peg is usually in the open position, with the key D retained in the casing A . The articles of dress having been hung upon the peg B and the stick, &c., inserted in the clamp G , the owner inserts a coin M in the slot l , whereby the chute E is made to release the slide C , as described. He then depresses the holder, thereby raising the slide, which is locked by the spring-beak e' , and thus also locks the holder, while the clamp G is locked by the incline C' of the slide. The key D is then withdrawn 105 and retained by the user. Before closing the holder B' , as described, he can raise the bar r , so as to indicate the number of articles on the peg, and this is then also locked in position, as described. For removing the articles from the peg the owner pushes in the key, so as to release the slide and allow spring b to open the holder, the key being at the same time secured in the casing.

If a counter is used, the disk H thereof 115 will be turned one division at each downward motion of the slide C , the resulting change of number of the indicating-disk being visible through a hole in the casing, as at Fig. 1.

As will be seen from the above, the improved locking wall peg or hook is of simple construction and manipulation and affords effectual security against the unauthorized removal of the articles of dress.

Having now particularly described and ascertained the nature of this invention and in what manner the same is to be performed, I declare that what I claim is—

1. The combination of peg or hook B , co-operating pivoted hook B' , casing A to which said parts are secured, a slide C within the casing and engaged by an end of hook B' , a spring normally depressing said slide and raising said hook B' to its open unlocked po- 130

sition, a pivoted coin-tube normally locking the slide down and hook B' open, said tube being mounted so as to be moved to release the slide and hook B' by insertion of a coin, whereby hook B' can be moved to its closed position, and a locking device automatically locking hook B' closed.

2. The combination of peg or hook B, co-operating pivoted hook B', casing A to which said parts are secured, a slide C within the casing and moved by hook B', a spring normally depressing said slide and moving hook B' to its open unlocked position, a coin-tube normally locking the slide down and hook B' open, and a locking device consisting of a spring-pressed hook carried by said slide, and a stop f in position to be engaged by said hook when the slide is raised thereby automatically locking hook B' closed.

3. The combination of peg or hook B, co-operating hook B', casing A to which said parts are secured, a slide C within the casing and engaged by an end of hook B', the engaging end of hook B' moving in a plane parallel with the direction of movement of the slide, a spring normally depressing said slide and raising hook B', a coin-tube normally locking the slide and hook B' open, said tube being moved to unlock the slide by insertion of a coin whereby hook B' can be moved to its closed position, a locking device automatically locking hook B' closed, said locking device requiring a special key for unlocking said hook B'.

4. The combination of peg or hook B, co-operating hook B', the engaging end of hook B' moving in a plane parallel with the direction of movement of the slide, a casing A to which said parts are secured, a slide C within the casing and engaged by an end of hook B', a spring normally depressing said slide and raising hook B', a coin-tube normally locking the slide and hook B' open, said tube being moved to unlock the slide by insertion of a coin whereby hook B' can be moved to its closed position, a locking device automatically locking hook B' closed and requiring a special key for unlocking said hook B', and means for locking the special key in its hole when the hook B' is unlocked, said means being constructed to release the key when hook B' is in locked position.

5. The combination of a casing, means for

holding articles supported outside the same, a slide in the casing, a pivoted coin-tube holding the slide in one position, a locking device for the slide operating when the slide is raised, said locking device requiring a special key to unlock it, and a pin g adapted to engage and hold the key in its hole when the slide is depressed.

6. The combination of a casing, a slide C therein movable in one direction by a spring b, a pivoted coin-tube engaging and holding the slide when it has been moved by said spring, the coin-tube being movable by insertion of a coin to release the slide, a spring-pressed device carried by said slide for locking the slide when it has been moved against the tension of the spring pressing on it, the casing having a keyhole through which a special key may be inserted to disengage said spring-pressed device, and hook B' operating the slide against the tension of spring b.

7. The combination of casing A, hook B', slide C normally locked in position with hook B' open, coin-controlled means for releasing the slide, means for locking the slide in position with hook B' closed, said means being key-operated for releasing the slide from such position, and a clamp G, said slide having a wedge end which when the slide is in position to lock hook B' locks said clamp.

8. The combination of a casing, a clamp G pivoted thereto, an end of the clamp extending into the casing, a slide C in the casing locking and releasing said clamp, and a coin-tube normally holding the slide in position to leave said clamp unlocked.

9. The combination of casing A, a holding or hanging device, indicator r, means for holding the indicator at the point at which it is set, slide C in the casing, coin-released means normally holding the slide in position with the hanging device open, and key-operated means holding the slide in position which it occupies when the hanging device is closed, and block t carried by the slide to lock said indicator when slide C is in its upper position.

Signed at Vienna, in the Empire of Austria-Hungary, this 7th day of June, 1898.

FRANZ AUSPITZ.
